[57] CLAIM

I claim the ornamental design for a combined outdoor floodlight and photo electric control therefor, as shown and described.

DESCRIPTION

FIG. 1 is a front elevational view of a combined outdoor floodlight and photo electric control therefor showing my new design;

FIG. 2 is a top plan view thereof;

FIG. 3 is a rear elevational view thereof;

FIG. 4 is a bottom plan view thereof; and

FIG. 5 is a right side elevational view thereof; the left side being a mirror image.

FIG. 6 is a front elevational view of a second embodiment of my new design;

FIG. 7 is a top plan view thereof;

FIG. 8 is a rear elevational view thereof;

FIG. 9 is a bottom plan view thereof;

FIG. 10 is a right side elevational view thereof, the left side being a mirror image.
